WATCH BAND DISPLAY CARTON OR SIMILAR ARTICLE

Robert P. Gust, Chicago, Ill., assignor to J. Major
Company, Chicago, Ill., a corporation of Illinois

Application September 17, 1949, Serial No. 5,048

Term of patent 7 years

(Cl. D80—5)

To all whom it may concern:

Be it known, that I, Robert P. Gust, a citizen of the United States, residing at Chicago, in the county of Cook and State of Illinois, have invented a new, original, and ornamental Design for a Watch Band Display Carton or Similar Article, of which the following is a specification, reference being had to the accompanying drawing, forming a part thereof.

Figure 1 is an exploded perspective view of a watch band display carton embodying my new design;

Figure 2 is a front view of the bottom portion of the carton, illustrating the display features of the watch band display carton shown in Figure 1;

Figure 3 is a side view of the bottom of the watch band display carton shown in Figure 2; and

Figure 4 is a top view of the bottom of the watch band display carton shown in Figures 2 and 3.

I claim:

The ornamental design for a watch band display carton or similar article, substantially as shown.

ROBERT P. GUST.
